AUTOMATIC HURDLE.

John E. Fecht, Dubuque, Iowa

Application September 21, 1937, Serial No. 164,937

3 Claims. (Cl. 272--59)

This invention relates to automatic hurdles of the type used for athletic purposes and has for an object to provide a hurdle which will afford maximum safety and protection to the athlete in his development and competition in track sports.

A further object is to provide a hurdle of this type which can be easily operated and may be approached from either side, also will be automatic in its return to a proper position when struck by a person jumping the hurdle.

A further object is to provide a device of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a front elevation, with parts in section, of an automatic hurdle constructed in accordance with the invention.

Figure 2 is a vertical sectional view taken on the line 2--2 of Figure 1 and showing in dotted lines the hurdle dislodged from normal position.

Figure 3 is a vertical sectional view of the centering mechanism.

Figure 4 is a detail cross sectional view taken on the line 4--4 of Figure 1 showing one of the telescopic standards.

Referring now to the drawings in which like characters of reference designate similar parts in the various views, 10 designates a U-shaped yoke which is formed integral with a tie rod 11 the ends of which project beyond the branches of the yoke and form trunnions 12 which are revolvably mounted in bearings 13 that are secured to telescopic spring extended standards 14 hereinafter more fully described. A cross bar 15 is connected at the ends to the ends of the branches of the yoke. The cross bar may be formed of a perforated metal sheet 16 covered with a rubber

50 facing 17.

The standards 14 each comprise telescopically assembled upper and lower tubes 18 and 19, the lower tubes being provided with elongated bases 20, both bases being connected by a tubular tie rod 21, as best shown in Figure 1. A pair of rods

22 are secured at the bottom in each lower tube 19 and sleeved upon the rods is a helical spring 23. The upper end of the spring is connected to a cap 24 which connects the upper ends of the rods. The lower end of the spring is connected to a pin 25 which extends between the rods and has the ends fixed to the inner tube 18 near the bottom thereof. The spring thus tends to yieldably hold the upper tube 18 in normal position but permits the upper tube to collapse into the lower tube 19 when the cross bar 16 is struck by a jumper, which position of the cross bar and of the standards is shown by dotted lines in Figure 2. The springs automatically return the standards to operative position after each actuation. 15

A lever 26 is pivotally connected at the bottom to the tie rod 21, as shown at 27 and is pivotally connected at the top to the yoke 10 as shown at 28. When the hurdle is struck by a jumper the lever 26 will be swung in a yoke on the lower 20 pivot pin 27 and will rock the yoke 10 on the gudgeons 13 at the same time exerting a downward pull on the yoke so that the springs of both standards will be compressed as the standards are telescoped, and store up energy to return the yoke 25 to normal position immediately after pressure has been released from the cross bar 16.

To assure that the cross bar 16 will automatically be centered in the plane of the tie rods 11 and 21 without undue rocking after each actuation, a lever 29 is pivotally connected at the upper end as shown at 30 to the yoke 10. The lower end of the lever enters a casing 31 which is provided with a split ring clamp base 32 which embraces the tie rod 21 and is bolted thereto as shown at 33. The casing is provided with a slot 34 in the top to permit the lever 29 swinging on a pivot pin 35 which is secured to hinge ears 36 on the tie rod 21, as best shown in Figure 3. 30 35

A helical spring 37 is sleeved on the lever 29. 40 The upper end of the sleeve abuts a stop collar 38 which is slidably received in the casing 31 and the bottom of the spring abuts a stop collar 39 which is adjustably mounted on the lever by a nut 40 to vary the tension of the spring. Stop shoulders 41 project inwardly from the walls of the slot 34 and form guides to direct swinging movement of the lever. 45

Each time the cross bar 16 is struck the lever 29 will be swung on its pivot pin 35 to the dotted 50 line position shown in Figure 2 and during such swinging movement, by virtue of the guide shoulders 34 being curved substantially in a radius struck from the lower tie rod 21, the spring 37 will be compressed and hold the cross bar 16 55

- against too free movement in a downward arc. The spring thus forms a brake. During return movement of the yoke and cross bar to normal position under urge of the springs 23 of the standards, the spring 37 of the centering device will expand and frictionally engage the stop shoulders 41 with sufficient friction to prevent undue rocking of the cross bar and yoke after the parts assume normal position.
- 10 From the above description it is thought that the construction and operation of the invention will be fully understood without further explanation.
- What is claimed is:
- 15 1. An automatic hurdle comprising a pair of telescoping spring controlled standards, a yoke pivotally secured to the upper ends of the standards, a cross bar connected at the ends to the ends of the branches of the yoke, a cross bar connecting the standards, a lever pivotally connected to the last named cross bar and to the yoke for swinging the bottom of the yoke when the first named cross bar is struck, and depressing the standards against the tension of their springs in such manner that expansion of the springs will instantly return the yoke to normal position.
- 20 2. An automatic hurdle comprising a pair of telescoping spring controlled standards, a yoke pivotally secured to the upper ends of the standards, a cross bar connected at the ends to the ends of the branches of the yoke, a cross bar connecting the standards, a lever pivotally connected to the last named cross bar and to the yoke for swinging the bottom of the yoke when the first named cross bar is struck, depressing the standards against the tension of their springs in such manner that expansion of the springs will instantly return the yoke to normal position.
- 25 3. An automatic hurdle comprising a pair of telescoping spring controlled standards, a yoke pivotally secured to the upper ends of the standards, a cross bar connected at the ends to the ends of the branches of the yoke, a cross bar connecting the standards, a lever pivotally connected to the last named cross bar and to the yoke for swinging the bottom of the yoke when the first named cross bar is struck, depressing the standards against the tension of their springs in such manner that expansion of the springs will instantly return the yoke to normal position.

30 nected to the last named cross bar and to the yoke for swinging the bottom of the yoke when the first named cross bar is struck, depressing the standards against the tension of their springs in such manner that expansion of the springs will instantly return the yoke to normal position, and means connected to the yoke and to the second named cross bar and adapted to center the yoke in normal position and prevent too free swinging movement of the yoke after each ac- 10 tuation.

3. An automatic hurdle comprising a pair of telescoping spring controlled standards, a yoke pivotally secured to the upper ends of the standards, a cross bar connected at the ends to the ends of the branches of the yoke, a cross bar connecting the standards, a lever pivotally connected to the last named cross bar and to the yoke for swinging the bottom of the yoke when the first named cross bar is struck, depressing the standards against the tension of their springs in such manner that expansion of the springs will instantly return the yoke to normal position, a lever connected to the second named cross bar and to the yoke, a casing for the lever, a collar loose on the lever and frictionally engaging the casing, and a spring sleeved on the lever and exerting pressure against the collar to prevent too free swinging movement of the yoke after each 15 20 25 30 actuation.

JOHN B. FECHT.
